LAURENCE E. TOPHAM, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

Application filed May 22, 1920, Serial No. 383,564. Renewed January 15, 1925.

The present invention relates to those operations in the manufacture of a shoe which are performed progressively along the bottom margin of a shoe while the assembled 5 parts of the shoe are supported upon a last to secure the parts together or prepare the shoe for further operations or give to parts of the shoe their final form or finish. An 10 object of the invention is to facilitate these operations and to enable them to be performed in an accurate and reliable manner and thus contribute to the production of 15 shoes uniform as to size, shape, construction and appearance without any substantial skill on the part of the workmen.

With this object in view the invention contemplates presenting the shoe successively to the operating means which are to perform the successive operations on the shoe, 20 utilizing an outline on the shoe of predetermined shape to determine the outline followed by the operating means during the performance of each operation and imparting predetermined tipping movements to the 25 operating means or shoe as predetermined points in the outline are reached to maintain the operating means and the shoe in the proper relative positions at the point of operation. Each operation is thus performed 30 in an accurate and reliable manner and since the path of each operating means and the direction, extent and timing of the correcting movements are predetermined, the results produced by each operating means are uniform 35 and bear a predetermined relation to the shoe and to the results produced by the other operating means. Not only does the present invention contribute to the production of shoes uniform as to size, shape, construction 40 and appearance, but the method is such that automatic machinery may be utilized in carrying out the several steps so that the cost of production can be reduced to a low figure and errors incident to the 45 use of unskilled or careless labor eliminated.

The invention is illustrated and described in the present application as applied, in the making of a welted shoe, to the stitching of the outsole of the shoe to the welt, and trimming off the projecting margin of the sole. 50 It is to be understood, however, that the invention is not limited to these particular op-

erations in making welted shoes, but certain features of the invention may be employed in other operations and in the making of 55 other classes of shoes.

In making a welted shoe, it is desirable that the edge of the shoe should be accurately trimmed off to a regular outline and that the seam by which the outsole is attached to 60 the welt, which is ordinarily termed the outseam, should be located at uniform distances from the trimmed edge of the sole respectively about the forepart of the shoe and along the shank. In sewing the outsole of a 65 shoe to the welt, ordinarily the shoe is guided either by means of a gage arranged to engage the edge of the sole or by a gage arranged to enter the crease between the welt and the upper so as to engage the upper close 70 to the inseam, the gage determining the position of the shoe transversely of the line of feed at the point of operation. In either case, the gage is located in one position in operating along the shank on the side of the 75 shoe first sewn to locate the seam relatively close to the upper, is shifted by the operator to another position in passing from the shank to the forepart to locate the seam close to the edge of the sole and is shifted back 80 to the first position in passing from the forepart to the shank on the opposite side of the shoe. The operating positions of the gage are fixed, the positions of the gage being determined by fixed stops, and the seam follows 85 a line substantially parallel with the outline engaged by the gage, this outline and the outline of the seam having substantially the same shape. When the outseam is located by means of a gage of this character 90 arranged to engage the edge of the sole the line of the seam follows the irregularities in the outline of the sole which is then only rough-rounded. When the outseam is located by means of such a gage arranged to 95 engage the upper adjacent the inseam, the outline engaged by the gage, which is determined to a large degree by the inseam, also has certain irregularities, such as those due to irregularities in the inseam and also those 100 due to the overlapping of the parts of the upper at certain points, which are reproduced in the seam line. Furthermore, the points at which the gage is shifted to change

the position of the seam is determined only by the eye and judgment of the operator with the result that the gage is often shifted at an improper point in the movement of the shoe past the stitching mechanism.

In trimming the edge of a sole as usually performed, the shoe is held in the hands of the operator and the outline to which the sole is trimmed is determined by the eye of the operator who attempts to trim off the sole on a line parallel with the line of the out-seam. The result is that the outline to which the sole is trimmed has certain irregularities due to irregularities in the line of the out-seam and other irregularities due to the imperfect guiding of the shoe during the trimming operation, and that there are variations in the distance at which the sole is trimmed from the outseam at different points in the margin of the sole. Edge trimming machines have been devised in which a gage arranged to engage the shoe is provided for guiding the shoe during the trimming operation. Where a gage is provided which engages the rough-rounded edge of the sole or where a gage is provided which engages the upper of the shoe close to the inseam, the outline engaged by the gage will have certain irregularities which will be reproduced in the trimming operation.

With these considerations in mind a further object of the present invention is to provide a method of making shoes by which an operating means may be caused to follow a regular even outline about a shoe bottom.

Also an object of the invention is to provide an improved method of stitching the outsole of a welted shoe to the welt and trimming off the projecting margin of the sole of the shoe which will obviate the disadvantages above pointed out.

With these objects in view, the invention consists in certain novel steps in the manufacture of a shoe hereinafter described and particularly pointed out in the claims.

In the accompanying drawings are illustrated a machine for stitching outsoles to the welts of welted shoes, and a machine for trimming off the projecting margins of shoe soles which may be employed in carrying out the present invention.

In the drawings, Fig. 1 is a view in front elevation of the machine for stitching outsoles to welts; Fig. 2 is a view in side elevation of the machine shown in Fig. 1; Fig. 3 is a detail plan view illustrating the jack supporting and actuating mechanisms and certain associated parts of the machine of Fig. 1; Fig. 4 is a detail plan view of a portion of the mechanism shown in Fig. 3; Fig. 5 is a detail plan view illustrating the mechanism of the machine of Fig. 1 for controlling the feeding movement of the shoe; Fig. 6 is a detail view in side elevation illustrating the parts of the machine of Fig. 1 en-

gaging the shoe at the point of operation; Fig. 7 is a view in front elevation of the machine for trimming off the projecting margins of shoe soles; Fig. 8 is a view in side elevation of the machine shown in Fig. 7; Fig. 9 is a detail plan view illustrating the mechanism for the machine of Fig. 7 for imparting feeding movements to the shoe; Fig. 10 is a view in side elevation illustrating the parts of the machine of Fig. 7 which engage the shoe at the point of operation; Fig. 11 is a plan view of the outsole of a shoe showing the same after the sole is rough-rounded; Fig. 12 is a view similar to Fig. 9 showing the outsole after the sewing of the same to the welt in accordance with the present process; and Fig. 13 is a view similar to Figures 11 and 12 showing the sole after the edge is trimmed in accordance with this process.

In the present process as applied, in the making of welted shoes, to the stitching of the outsole of a shoe to the welt and trimming off the projecting margin of the sole, after the outsole has been applied to the shoe bottom and the sole has been laid and rough-rounded, the shoe is presented to an outsole stitching mechanism and during the stitching operation predetermined relative movements are imparted to the stitching mechanism and the shoe to locate the shoe in the proper position with relation to the stitching mechanism as the point of operation is transferred about the shoe. Preferably the proper relative positions of the stitching mechanism and the shoe are maintained by imparting movements to the shoe. The position of the shoe transversely of the line of feed during the stitching operation is determined by engaging a gaging device with a certain outline on the shoe. During the stitching operation the gaging device is moved to compensate for the irregularities in the outline engaged by the engaging device so as to cause the seam to follow a regular outline. Preferably the gaging device is engaged with the upper of the shoe at some distance above the crease between the projecting margin of the sole and the upper. The outline thus engaged by the gaging device is determined by the shape of the last above the last bottom and is uniform in shape in shoes of the same style, this outline varying only in dimensions in different sizes of shoes of the same style. The uniformity in this outline in different shoes of the same style enables the shoe to be guided properly with relation to the operating means by imparting the same movements to the gaging device in operating upon different shoes, the time relation of the movements of the gage and the feeding movements of the shoe being varied to suit shoes of different sizes.

The outline above described, which is engaged by the gaging device, has a non-paral-

rel relation to the predetermined line which the seam is to follow throughout considerable distances along certain parts of the shoe bottom or said outline has an entirely different shape from the predetermined outline along which the seam is to be sewn. The gaging device is moved during the operation to compensate for the difference in shape between the outline engaged by the gaging device and the predetermined outline which the seam is to follow. The outline thus engaged by the gaging device has certain irregularities such as at the toe where the parts of the upper overlap. During the operation the 10 gaging device is moved to compensate for the irregularities in the outline engaged by said device so that the seam will follow a regular smooth even outline.

After the outsole has been stitched to the 20 welt in this manner, at the proper stage in the further manufacture of the shoe, the shoe is presented to an edge trimming mechanism. During the edge trimming operation predetermined relative movements are imparted to the shoe and the edge trimming mechanism to locate the shoe in proper position with relation to said mechanism as the point of operation is transferred about the shoe. In the edge trimming operation also the position of the shoe transversely of the line of feed is determined by engaging a gaging device with a certain outline on the shoe. This gaging device is moved during the sole trimming operation to compensate for the 30 irregularities in the outline engaged by the gaging device so as to cause the shoe to be trimmed to a regular outline. The gaging device is preferably engaged with an outline on the shoe which is uniform in shoes of the same size and style, and is of uniform shape in different shoes of the same style so that the different shoes may be guided properly with relation to the trimming mechanism by imparting the same movements to the gaging device. The relative movements imparted to the trimming mechanism and the shoe during the trimming operation will usually be the same or substantially the same as the relative movements imparted to the 40 stitch forming mechanism and the shoe during the stitching operation. Preferably the relative positions of the trimming mechanism and the shoe are maintained by imparting movements to the shoe. Preferably also the gaging device is engaged with the same outline on the shoe during the trimming operation as the outline engaged by the gaging device in the stitching operation. When the movements imparted to the shoe in the stitching operation and in the trimming operation are the same, and the sole is to be trimmed off on a line parallel with the line of the outseam as is the present practice in shoe manufacture, the same movements will

be imparted to the gage in the trimming operation as in the stitching operation.

In the manufacture of a welted shoe the stitching of the outsole of a shoe to the welt and the trimming of the projecting margin of the shoe sole in the manner above described may be advantageously carried out by placing the shoe at the proper stage in the manufacture thereof in the machine shown in Figures 1 to 6 inclusive to stitch the outsole to the welt and thereafter placing the shoe in the machine shown in Figures 7 to 13 inclusive to trim off the projecting margin of the sole.

The machine for stitching outsoles to 50 welts shown in Figures 1 to 6 inclusive has the same construction, arrangement and mode of operation of parts as the machine illustrated and described in applicant's pending application Serial No. 255,209, filed September 21, 1918.

The sewing mechanism of the machine shown in these figures comprises a curved hook needle, a curved awl 4, a work support 6, and a presser-foot 8. The machine is provided with a jack 12 for supporting the shoe 55 during the sewing operation.

The jack 12 is mounted on the upper end of a spindle 14, supported at its lower end. The supporting devices for the spindle comprises a wheel 16 rotatably mounted on a stud 18 and connected with the spindle by a gimbal joint. The stud 18 is supported at the forward end of a yoke 20, pivoted to swing in a vertical plane on a second yoke 22. The yoke 22 in turn is pivoted to swing in a horizontal plane on a link-frame 24, carried by and connecting the swinging arms 26 and 28. The forward end of the yoke 20 is held up yieldingly by means of a coiled spring 30.

During the sewing operation the shoe is held at all times at the point of operation by the engagement of the work support, presser-foot, needle and awl with the projecting margin of the sole. Relatively slight vertical movements are imparted to the jack and shoe by the cooperative action of spring 30 and the work support and presser-foot, the work support and presser-foot acting as guides for the shoe. The supporting devices for the jack spindle permit the lower end of the spindle to be freely moved horizontally in any direction, and also permit the jack to tip freely in any direction about the lower end of the spindle. Longitudinal and lateral tipping movements and lateral turning movements are imparted to the jack and thereby to the shoe to position the shoe properly with relation to the stitch forming devices as the point of operation is transferred about the shoe. The required tipping movements are imparted to the jack by devices acting to move the lower end of the

spindle forward, rearwardly and laterally of the machine, and the required turning movements are imparted to the jack by devices acting to rotate the jack spindle. Because of the fact that the shoe is held at all times at the point of operation by the devices engaging the shoe, the tipping and turning movements imparted to the shoe are caused to take place about these devices as 10 a fulcrum.

The arm 26 is actuated to impart forward and rearward movements to the lower end of the jack spindle by means of a lever 34, connected with the arm 26, and a cam roll 36 mounted on said lever and arranged to engage in a cam groove 38 in a cam disk 40, mounted on a cam shaft 42 which for convenience will be hereinafter termed the pattern cam shaft. The yoke 20 is actuated to 20 move the lower end of the spindle laterally by mechanism comprising a bell crank lever 43 and a link 44 connecting the yoke 20 with the bell crank lever. A lever 46 is connected with the bell crank lever and carries a cam roll 48 engaging in a cam groove 50 also formed in the cam disk 40. The wheel 16 is actuated to rotate the jack spindle by mechanism comprising a cable 52, passing about the wheel 16 and about a series of 30 guide rolls 54, 56, 58, 60 and 62, a pivoted segment 64 to which one end of the cable is secured, and a weight 66 secured to the other end of the cable. The swinging movements of the segment 64 are produced and controlled by a cam lever 68, one arm of which is connected with the segment 64 by intermeshing gear segments and the other end of which carries a cam roll 70 arranged to engage a cam face 72, formed on a cam disk 35 40 74, mounted on the cam shaft 42.

The jack spindle is acted upon intermediate its lower end and the jack by mechanism tending yieldingly to swing the jack about the connection between the lower end of the 45 spindle and the wheel 16 toward the rear of the machine. This mechanism comprises a rod 76 connected at its forward end with the jack spindle and acted upon at its rear end by devices tending yieldingly to move the rod rearwardly. The devices are arranged to act upon the rod with a variable force and are controlled by certain movements of the jack spindle during the operation of the machine. This mechanism acting 50 55 on the jack tends to maintain the shoe at all times during the stitching operation in its proper rearward position with relation to the stitching mechanism at the point of operation.

The machine for stitching outsoles illustrated in the drawings is also provided with a movable gage indicated at 78 for guiding the shoe to determine the distance at which the seam is formed from the edge of the shoe 60 65 sole. The gage is pivotally mounted at 80

on an arm on the frame of the machine and is constructed and arranged to extend upwardly from its pivotal point to a point just below the work support 6 so that its upper end will engage the upper of the shoe. The gage thus engages the upper of the shoe at a point at some distance from the crease and the outline engaged by the gage is determined by the last and will be of uniform shape on different shoes of the same style, 75 the outline varying only in dimensions on such shoes of different sizes. The gage actuating devices of the machine operate under normal conditions to hold the gage at all times positively in contact with the upper of 80 the shoe so that the position of the shoe is determined by the gage throughout the operation of the machine to cause the seam to be formed at the proper distance from the edge of the shoe at all points in the sole 85 margin. The outline engaged by the gage is considerably different in shape from that which the seam is to follow and the gage is moved to compensate for the differences in shape between these two outlines. The gage 90 engaging contour of the shoe is irregular in outline at certain points, the irregularities in the same being due to the overlapping of the parts of the upper at certain points. In order that these irregularities may not be 95 reproduced in sewing the outseam, the gage 78 is actuated to compensate for these irregularities so that the seam follows a regular outline.

The gage is also actuated to compensate 100 for certain of the positioning movements imparted to the shoe during the stitching operation which tend to vary the forward or rearward position of the projecting margin of the sole at the point of operation transversely of the line of feed. In order that the seam may be located farther from the upper about the forepart of the sole than along the shank, the gage is advanced in passing from the shank to the forepart as 105 the first side of the shoe is sewn, and is retracted in passing from the forepart to the shank on the opposite side of the shoe.

The mechanism for actuating the gage in this manner comprises an arm 82, also pivoted at 80 and having a projection arranged to engage an abutment of the gage. The gage is held normally in contact with the projection on the arm 82 by the engagement of the shoe with the gage. The lower end of the arm 82 engages an eccentric 84 secured to a rock shaft 86. The rock shaft is rotated to advance and cause the retraction of the gage by means of a gear segment 88 secured to the rock shaft and an intermeshing gear 115 segment 90 formed on a swinging arm 92 secured to a rock shaft 94. To the rock shaft 94 is secured a second arm 96 which carries a roll engaging a contact face formed on the outer end of an arm 98 secured to a vertical 120 125 130

shaft 100. To the shaft 100 is secured a second arm 102 upon which is mounted a cam roll 104 engaging a cam face 106 formed on the cam disk 40.

5 Feeding movements are imparted to the shoe by the movements of the awl 4 in the line of feed. When a shoe is placed in the machine the mechanism for driving the pattern cam shaft is adjusted in accordance 10 with the size of the shoe for a predetermined rate of feed of the shoe. In order that the positioning mechanism may operate to position the shoe properly with relation to the stitch forming mechanism, as the point of 15 operation is transferred about the shoe it is important that the shoe shall be fed at or substantially at the predetermined rate with relation to the speed of the pattern cam shaft throughout the operation. For certain reasons 20 variations from the predetermined rate of feed often occur in the feeding movements imparted to the shoe by the awl, thereby placing the shoe out of time with the cam shaft. To obviate this difficulty, mechanism 25 is provided which operates automatically upon the occurrence of an increase or a decrease in the rate of feed of the shoe from the predetermined rate of feed to adjust the feeding mechanism to diminish or increase 30 the rate of feed and thereby restore the shoe to its proper time relation to the cam shaft.

The mechanism for controlling the rate of feed of the shoe comprises a lever 108 pivoted at 110 on the frame, a lever 112 pivotally mounted at 114 on the lever 108, and a bar or link 116 connecting the lever 112 with the toe end of the jack. During the operation of the machine the lever 108 is swung to the left in timed relation to the rotation of the pattern cam shaft. The mechanism for actuating the lever 108 comprises a triangular lever 118, pivotally mounted at 120 on a hanger 122, and pivotally connected at 124 35 with the lever 108. The hanger 122 is pivotally supported at 126 on a lever 128 pivoted at 130 on the frame. The lever 128 is locked in position during the sewing operation, and the lever 118 with the hanger 122 40 is swung about the pivot 126. The mechanism for thus actuating the lever 118 comprises a lever 132 pivoted at 134, and connected with the lever 118 by a link frame 136, a cam lever 138 and a link 139 connecting the cam lever with the lever 132. The cam lever 138 carries a cam roll 140 arranged to engage a cam face 142 formed on 45 the cam disk 74.

The lever 112 carries a series of electrical contacts by which a series of circuits controlling the mechanism for adjusting the feeding movements of the awl may be made or broken. The lever 108 is actuated so that, when the shoe is fed at the predetermined 50 rate, there will be no pivotal movement of

the lever 112 relatively to the lever 108, and the circuits controlled by the lever 112 will remain open. When, however, the rate of feed of the shoe falls below the predetermined rate, the pivotal movement of the 70 lever 112 relatively to the lever 108 will close certain of the electrical circuits and cause an adjustment of the feeding devices to increase the rate of feed of the shoe. In a corresponding manner, when the rate of feed 75 of the shoe rises above the predetermined rate of feed, the swinging movement of the lever 112 will close certain of the electrical circuits and cause an adjustment of the feeding devices to decrease the rate of feed of 80 the shoe.

Through the connections between the lever 128 and the jack, said lever and the fulcrum of the lever 118 are adjusted in accordance with the size of the shoe to be sewn upon the 85 placing of the shoe in the machine in position to start the seam. The lever 128 controls the mechanism for driving the pattern cam shaft, the speed of said cam shaft being adjusted in accordance with the size of the 90 shoe by the adjustment of the lever 128. Thus the cams 38, 50, 72, 106 and 142 may be employed in operating upon different sizes of shoes of the same style.

After the outsole has been stitched to the 95 welt, in the further carrying out of the present process, the shoe may, at the proper stage in the further manufacture of the shoe, be presented to the machine shown in Figures 7 to 10 inclusive for the purpose of 100 trimming off the edge of the sole. In this machine the movements imparted to the shoe are practically identical with those which are imparted to the shoe during the stitching of the outsole upon the machine shown 105 in Figures 1 to 6 inclusive.

The machine shown in Figures 7 to 10 inclusive has the same construction, arrangement, and mode of operation of parts as the machine illustrated and described in applicant's pending application Serial No. 110 355,820, filed February 2, 1920.

This machine comprises two rotary edge trimming tools 144 and 146, mounted on a vertical shaft 148. The shoe is supported at 115 the point of operation by means of a work table 150 arranged to engage in the crease between the projecting margin of the sole and the upper, the sole resting on the upper surface of the table. The shaft 148 is 120 mounted on a carriage which is arranged for adjustment to locate either of the cutters 144 and 146 in operating position.

During the operation of the edge trimming machine on the shoe, the shoe is supported upon a jack 152. This jack has the same construction as the jack 12 of the machine for stitching outsoles shown in Figures 1 to 6 inclusive, and is supported and actuated by mechanism having the same con- 125 130

structure, arrangement and mode of operation as the mechanism for supporting and actuating the jack 12. The mechanism for supporting the jack 152 comprises a wheel 154, a yoke 156, a second yoke 158, a link frame 160 and swinging arms 162 and 164. The forward end of the yoke 156 is held up yieldingly by a coiled spring 166.

During the trimming operation the shoe 10 is held at all times at the point of operation by the engagement of the work support 150 with the projecting margin of the sole. Relatively slight vertical movements are imparted to the jack and shoe by the co-operative action of the spring 166 and the work support, the work support acting as a guide for the shoe. In the edge trimming machine the same longitudinal and lateral tipping movements and lateral turning 15 movements are imparted to the jack and thereby to the shoe to position the shoe properly with relation to the trimming cutter as are imparted to the jack and shoe in the machine for stitching outsoles. The tipping movements are imparted to the jack by moving the lower end of the jack spindle forwardly, rearwardly and laterally of the machine, and the turning movements are imparted to the jack by rotating the jack spindle, the movements thus imparted to the jack spindle tipping and turning the shoe 20 about the work support as a fulcrum.

The arm 162 is actuated to impart lateral tipping movements to the shoe by mechanism comprising a lever 168 connected with said arm and a cam roll 170 mounted on said lever and engaged in a cam groove in a cam disk 172 mounted on a cam shaft 174 which constitutes the pattern cam shaft of the machine. The cam groove in which the cam roll 170 engages has the same shape as the cam groove 38 in the cam disk 40 of the machine shown in Figures 1 to 6 inclusive. The yoke 156 is actuated to impart longitudinal tipping movements to the shoe by mechanism comprising a bell crank lever 175, a link 176 and a lever 178. The lever 178 carries a cam roll 180 also engaging in a cam groove in the cam disk 172. The cam groove in which the cam roll 180 engages has the same shape as the cam groove 50 in the cam disk 40 of the machine for stitching outsoles. The mechanism of the edge trimming machine for imparting lateral turning movements to the jack comprises a cable 182, a pivoted segment 184, a weight 186 and a cam lever 188. The cam lever 188 carries a cam roll 190, arranged to engage a cam face 192 formed on a cam disk 194, mounted on the pattern cam shaft 174. The cam face 192 has the same shape as the cam face 72 on the cam disk 74 of the machine for stitching outsoles.

By the mechanism described, the same forward, rearward and lateral movements and

the same turning movements are imparted to the jack spindle in the edge trimming machine as in the machine for stitching outsoles. The point at which the shoe is engaged by the work support 150 in the edge 70 trimming machine has the same relation to the mechanism for supporting and actuating the jack as the point at which the shoe is engaged by the work support, presser-foot, needle and awl of the machine for stitching outsoles has to the mechanism for supporting and actuating the jack 12 in this machine. The movements of the jack in the edge trimming machine, therefore, will impart the same tipping and turning movements to the shoe as are imparted to the shoe in the machine for stitching outsoles.

In the edge trimming machine the shoe is fed by feeding movements imparted to the jack. The mechanism for actuating the 85 jack to impart feeding movements to the shoe in this machine comprises a feeding lever 196 pivoted at 198 on the frame, and a bar or link 200 connecting the feeding lever with the toe end of the jack. During 90 the operation of the machine the feeding lever 196 is swung to the left in timed relation to the rotation of the pattern cam shaft, thereby actuating the jack to advance the marginal portion of the shoe past 95 the edge cutting tool. The mechanism for actuating the lever 196 in this manner has the same construction, arrangement and mode of operation as the mechanism for actuating the lever 108 of the machine for stitching 100 outsoles. The mechanism for actuating the lever 196 comprises a triangular lever 202, a hanger 204, a lever 206, a lever 208, a link frame 210, a cam lever 212 and a link 214. The cam lever 212 carries a cam roll 216 engaging a cam face 218 formed on the cam disk 194. The cam face 218 has the same shape as the cam face 142 on the cam disk 74 of the machine for stitching outsoles. The shoe will thus be fed at the same rate 110 relative to the speed of the pattern cam shaft in the edge trimming machine as in the machine for stitching outsoles.

The lever 206 and the fulcrum of the lever 202 are adjusted in accordance with the size 115 of the shoe to be trimmed upon the placing of the shoe in the machine in position to start the trimming operation and the adjustment of the lever 206 also adjusts the speed of the pattern cam shaft in accordance with the size of the shoe.

The edge trimming machine is provided with a movable gage indicated at 220 for guiding the shoe to determine the distance 120 at which the shoe is trimmed from the upper. The gage is pivotally mounted at 222 on an arm on the frame, and extends upwardly from its pivotal point to a point below the work support 150, the gage 220 engaging the shoe at the same distance from 125

the projecting margin of the sole as the gage 78 of the machine for stitching outsoles. The outline engaged by the gage 220, therefore, is the same as the outline engaged by 5 the gage 78. The shoe is maintained in contact with the gage 220 at all times during the trimming operation, the gage determining the distance from the upper at 10 which the shoe sole is trimmed off throughout the operation. The gage 220 has the same relation to the devices for supporting and actuating the jack 152 as the gage 78 of the machine for stitching outsoles has to the mechanism for supporting and actuating 15 the jack 12. The same movements are imparted to the gage 220 during the trimming operation as are imparted to the gage 78 during the stitching of the outsole to the 20 welt. The outline engaged by the gage has a different shape from the shape of the outline to which the sole is to be trimmed and the gage is moved to compensate for the difference in the shape of the two outlines. 25 As is the case with the gage 78, the gage 220 is actuated to compensate for irregularities in the outline engaged by the gage so that the shoe is trimmed to a regular outline. The gage is also actuated to compensate for 30 certain of the positioning movements imparted to the shoe during the operation which tend to displace the projecting margin of the sole with relation to the trimming cutter. In order that a somewhat 35 wider margin may be left on the sole about the forepart than along the shank, the gage is advanced in passing from the shank of the sole to the forepart in trimming the sole on first side of the shoe and is retracted in 40 passing from the forepart to the shank in trimming the sole on the opposite side of the shoe.

The mechanism for actuating the gage 220 comprises a rock shaft 224, an eccentric 45 226 upon which the lower end of the gage rests, gear segments 228 and 230, an arm 232, a rock shaft 234, an arm 236, an arm 238, a vertical shaft 240 and an arm 242. The arm 242 carries a cam roll 244 arranged 50 to engage a cam face 246 on the cam disk 172. The cam face 246 has the same shape as the cam face 106 on the cam disk 40 of the machine for stitching outsoles.

With the gage 220 actuated and controlled in the above manner, the shoe will be 55 guided by the gage in the same path as the shoe is guided by the gage 78 of the machine for stitching outsoles. The edge trimming cutters are, of course, located so that the cutting point is somewhat farther back 60 with relation to the gage than the point of operation of the needle and awl of the machine for stitching outsoles with relation to the gage 78. Thus the sole of the shoe will be 65 trimmed off by the trimming cutters along a line parallel with the outseam or at

a uniform distance from the outseam at all points in the margin of the shoe bottom.

Fig. 11 of the drawings illustrates in plan a shoe bottom after the sole of the shoe has been rough-rounded, the junction line of the 70 upper and the projecting margin of the sole being indicated by the double dot and dash line *a* in this figure. It will be noted from this figure that the outline of the outsole has certain irregularities and that the outsole has a somewhat wider margin about the toe portion of the sole than along other parts of the margin of the sole. This increase in the width of the projecting margin of the sole is due to the increase in the 75 thickness of the upper materials engaged by the gage in the rough-rounding machine when operating about the toe.

Fig. 12 illustrates a shoe bottom after the outsole of the shoe has been stitched to the welt in accordance with applicant's method. In Figures 11 and 12 the outline engaged by the gaging device by which the shoe is guided during the stitching operation is indicated by the single dot and dash line *b*. It will be noted from this figure that the line of the outseam indicated by dotted line *c* does not follow the irregularities in the rough-rounded edge of the sole, but that the seam is sewn to a regular even outline.

Fig. 13 illustrates a shoe bottom after the outsole has been trimmed in accordance with the present method, the outline engaged by the gaging device to guide the shoe during the trimming operation being indicated by single dot and dash line *d* and the line of the outseam by dotted line *c* in this figure. It will be noted from this figure that all the irregularities occurring in the margin line of the rough-rounded outsole are removed in the trimming operation, the shoe being trimmed to a regular even outline. Also the trimmed edge of the sole is located at a uniform distance from the outseam at all points in the sole margin.

Having explained the nature and object of the invention, and specifically described a manner in which the invention may be carried out, what is claimed is—

1. The process of making shoes which comprises guiding a shoe during the presentation of the shoe to an operating means by engaging a gaging device with an outline on the shoe above and parallel with the last bottom and moving the gaging device during the operation to cause the operating means to follow a different predetermined outline.

2. The process of making shoes which comprises presenting a lasted shoe to an operating means, guiding the shoe during the operation of the operating means on the forepart and shank thereof by engaging a gaging device with an outline on the shoe deter-

mined by the shape of the last and moving the gage to cause the operating means to follow a different outline.

3. The process of making shoes which 5 comprises forming the outseam of a shoe along an outline different from but in predetermined relation to a certain outline on the shoe and trimming off the projecting margin of the shoe sole to an outline different from but in predetermined relation to said shoe outline.

4. The process of making shoes which 15 comprises presenting a shoe to an operating means and guiding the shoe during the operation of the operating means thereon to cause the operating means to follow an outline different from but having a predetermined relation to a certain contour on the shoe, thereafter presenting the shoe to a 20 second operating means and guiding the shoe during the operation of the second operating means thereon to cause the second operating means to follow an outline different from but having a predetermined relation to the 25 same contour.

5. The process of making shoes which 30 comprises forming the outseam of a shoe along an outline different from but in predetermined relation to a certain contour on the shoe and trimming off the projecting margin of the sole in predetermined relation to the 35 outseam.

6. The process of making shoes which 35 comprises guiding a shoe during the stitching of an outsole to the welt by engaging a gaging device with a certain contour on the shoe and moving the gaging device during the stitching operation to compensate for irregularities in said contour and guiding the 40 shoe during the trimming off of the projecting margin of the sole by engaging a gaging device with a certain contour on the shoe and moving the gaging device during the trimming operation to compensate for irregularities in said contour.

7. The process of making shoes which 50 comprises imparting predetermined relative positioning movements to a shoe and the stitching forming mechanism during the stitching of the outsole to the welt and guiding the shoe during the stitching operation by engaging a gaging device with a certain contour on the shoe and imparting predetermined movements to the gaging device during the stitching operation, and imparting relative positioning movements the same in direction and extent to the trimming mechanism and the shoe during the trimming of the projecting margin of the sole and guiding the shoe during the trimming operation by engaging a gaging device with the same contour on the shoe and imparting movements the same in direction and extent to the gaging device as those imparted during the stitching operation.

8. The process of making shoes which comprises forming the outseam of a shoe in predetermined relation to a certain contour on the shoe determined by the shape of the last and trimming off the projecting margin of the shoe sole in predetermined relation to said contour.

9. The process of making shoes which 75 comprises forming the outseam of a shoe along an outline different from but in predetermined relation to a certain outline on the shoe and thereafter trimming off the projecting margin of the shoe sole to an outline different from but in predetermined relation to said shoe outline.

10. The process of making shoes which 80 comprises presenting a lasted shoe to an operating means, guiding the shoe during the operation of the operating means on the forepart thereof by engaging a gaging device with an outline on the shoe determined by the shape of the last and moving the gage during the operation.

11. The process of making shoes which 90 comprises guiding a shoe during the operation on the shoe to an operating means by engaging a gaging device with an outline on the shoe above and parallel with the last bottom, and moving the gaging device as 95 predetermined points in the outline are reached to cause the operating means to follow a different predetermined outline.

12. The process of making shoes which 100 comprises presenting a lasted shoe to an operating means, causing the operating means to follow an outline determined by an outline of the shoe, imparting relative tipping movements to the shoe and operating means to maintain their proper relative positions as certain predetermined points in the 105 outline operated upon are reached, thereafter presenting the shoe to a second operating means, causing said second operating means to follow an outline determined by an outline of the shoe and imparting relative tipping movements the same in direction and extent to the shoe and said second operating means as corresponding points in the 110 outline operated upon are reached.

13. The process of making shoes which 115 consists in presenting a shoe having one or more guiding outlines of predetermined shape successively to a plurality of operating means, causing each operating means to follow an outline determined by one of said 120 guiding outlines, and imparting predetermined tipping movements to the shoe to maintain it in proper position with relation to the operating means as predetermined points in the outline operated upon are 125 reached.

14. The process of making shoes which 130 comprises presenting a lasted shoe to an operating means, causing the operating means to follow an outline determined by an outline

of the shoe, imparting predetermined relative tipping movements to the shoe and operating means to maintain their proper relative positions as certain predetermined points in the outline operated upon are reached, thereafter presenting the shoe to a second operating means, causing said second operating means to follow an outline

determined by the same outline of the shoe **10** and imparting predetermined relative tipping movements to the shoe and said second operating means to maintain their proper relative position as corresponding points in the outline operated upon are reached.

LAURENCE E. TOPHAM.
